(57) **CLAIM**

The ornamental design for an outdoor space heater, as shown and described.

DESCRIPTION

FIG. 1 is a perspective view of an outdoor space heater showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines shown in the figures depict portions of the outdoor space heater that form no part of the claimed design.
